DESIGN FOR A BOX WRAPPER

Bernice Witmyer, Harrisburg, Pa., assignor to Woodward & Lothrop, Inc., a corporation of the District of Columbia

Application December 16, 1940, Serial No. 97,243

Term of patent 3½ years

To all whom it may concern:

Be it known that I, Bernice Witmyer, a citizen of the United States, residing in the city of Harrisburg, in the county of Dauphin, in the Commonwealth of Pennsylvania, have invented a new, original, and ornamental Design for a Box Wrapper, of which the following is a specification, reference being had to the accompanying drawing, forming part thereof.

The figure is a plan view of a box wrapper,
showing my new design.

I claim:

The ornamental design for a box wrapper, as shown.
